UNITED STATES PATENT OFFICE.

BALTZAR E. BOLLING, OF CHICAGO, ILLINOIS, ASSIGNOR TO J. K. STEWART MANUFACTURING COMPANY, OF CHICAGO, ILLINOIS, A CORPORATION OF ILLINOIS.

PARCEL-POST-RATE INDICATOR.

1,153,539.

Specification of Letters Patent. Patented Sept. 14, 1915.

Application filed September 16, 1914. Serial No. 861,927.

To all whom it may concern:

Be it known that I, BALTZAR E. BOLLING, a citizen of the United States, residing at Chicago, in the county of Cook and State 5 of Illinois, have invented new and useful Improvements in Parcel-Post-Rate Indicators, of which the following is a specification, reference being had to the accompanying drawings, forming a part thereof.

10 The purpose of this invention is to provide an improved device of the nature of a calculating machine for the purpose of conveniently ascertaining the amount of postage required upon any parcel which may be 15 sent by parcel post in accordance with its weight and the zone to which it is to be sent.

It consists in the elements and features of construction shown and described as indicated in the claim.

20 In the drawings Figure 1 is a perspective view of a device embodying this invention. Fig. 2 is a view of the entire circumferentially inclosing wall or shell of the casing of the device unrolled or extended flat so 25 that it may be entirely seen in a single view. Fig. 3 is a transverse section at the plane indicated by the line 3—3 on Fig. 1. Figs. 4, 5, 6 and 7 are diametric sections at the lines 4—4, 5—5, 6—6 and 7—7, respectively on 30 Fig. 3. Fig. 8 is an elevation of the panel devoted to the first and second zones.

The device shown in the drawings comprises a cylinder, 1, having imprinted upon it in tabular form certain numbers whose 35 significance and arrangement is hereinafter described, and a case in which said cylinder, 1, is mounted for rotation about its axis, said case comprising heads, 2, 2, in which trunnions, 3, 3, of the cylindrical member 1, 40 are journaled and outside of which said trunnions are provided with knurled heads, 4, 4, for rotating said cylindrical member. Said case further comprises the circumferentially extending shell, 5, which is fixed 45 with respect to the heads, 2, 2, and is subdivided longitudinally into panels. Said sub-division may be made merely by lines of ruling on the outer surface of the shell, 5, and for reasons hereinafter stated it is 50 preferably made by making said shell definitely polygonal in cross section the heads, 2, 2, being in that case of similar form as illustrated.

To adapt the device to the present United 55 States parcel post statute and regulations,

the shell is divided into eight (8) panels being octagonal in cross-sections.

The matter printed upon the cylinder, 1, disregarding for the present the two left-hand columns, comprises columns of numbers as follows: First a column, *a*, of numbers indicating weight expressed in pounds from 1 to 20, corresponding to the present parcel post statute; but any other arithmetical series of numbers indicating quantity 60 may be substituted, according to the precise use to which the implement is to be put, and the particular regulations to which it is to conform; second, columns *b*, *c*, *d*, *e*, *f* and *g*, in the order indicated from left to right, 65 containing numbers indicating the amount of postage necessary in the 3rd, 4th, 5th, 6th, 7th and 8th zones for the weights indicated in column *a*, termed a "base" column. It will be understood therefore that 70 the numbers in column *b*, being the postage required in the 3rd zone, are resultants of the number indicating pounds in column *a*, compounded with a constant multiplier and increment prescribed as the pound rate for 75 the 3rd zone; and that the numbers in column *c* are similarly resultants of the numbers in column *a*, compounded with a constant multiplier and increment prescribed as the pound rate for the 4th zone, each column 80 at the right of column *a* containing numbers which are resultants of the numbers in column *a* compounded with a constant multiplier and increment, the multipliers and increments being distinctive of each of 85 the several resultant columns and liable to be different for each of said columns respectively.

Each of the panels of the circumferentially extending casing, 5, except panel 10 90 which is conveniently used for explaining the mode of computation in the 1st and 2nd zones, which is special under the present statute, and panel, 20, which is devoted to "local rates," is devoted to a particular 95 zone; and contains two apertures, one at the left positioned for registering with the numbers in column, *a*, (base column), and the other positioned for registering with the numbers in the resultant column for the particular zone to which the panel is devoted. Thus, in panel, 30, for the 3rd zone, aperture 31, is positioned for reading through it the weight indicating numerals of column 100 *a*, and aperture, 32, is positioned for reading 105 *a*, and aperture, 32, is positioned for reading 110

through it the numbers indicating the postage in the 3rd zone. So in panels, 40, 50, 60, 70 and 80, apertures, 41, 51, 61, 71 and 81 register with the base column and apertures 42, 52, 62, 72 and 82 register respectively with resultant columns *c, d, e, f* and *g*.

From the foregoing description it will be understood that the operator taking the instrument in hand and holding it by the hollow casing, with the panel corresponding to the particular zone in respect to which he desires information in view, will rotate the cylinder by means of the protruding knurled knobs to bring the figures denoting the weight of the parcel in hand into registering with the left-hand aperture of said panel; and when the proper weight appears at this aperture, he will read through the right-hand aperture of the panel in question, the amount of the postage necessary for the parcel of the weight denoted by the figures appearing in the left-hand aperture.

Panel 10 is conveniently used for any general instructions which will assist the operator in using the instrument. As illustrated it contains a statement according to the present United States statute and postal regulations of the rule for computing parcel post rates in the 1st and 2nd zones. It will be understood that this particular printed matter merely illustrates the use to which this panel may be put for containing any desirable instructions.

By reason of the fact that under the present United States parcel post statute and regulations, local rates upon certain classes of articles are provided up to fifty pounds, which differ from the rates which would be ascertained from the instructions on panel 10 and which have no definite relation to the rates which would be ascertained with regard to the zones from 3rd to 8th inclusive, the instrument may contain provision for indicating these special local rates. For that purpose the two left-hand columns of the cylinder 1, are devoted respectively to numbers indicating weights from one pound to

fifty pounds and the rates for said weights respectively; and panel 20 is provided with two apertures, 21 and 22, for registering respectively with the said weight and rate columns; so that the operator desiring to ascertain these local rates for any given parcel will rotate the cylinder until the figures denoting the weight limits between which the weight of his parcel falls appear in the left-hand aperture, 21, in panel 20 and he will then be able to read in aperture, 22, of said panel the proper postage for the parcel.

As indicated above the sub-division of the circumferentially extending shell into panels may be made by any means sufficient to distinguish the panels to the eye, but, by making the shell itself polygonal so that the panels each constitute one side of the polygon or polygonal prism the angles thus formed afford the necessary demarcation. One specific advantage of adopting this means of defining the zones is that the device is thereby rendered stable when laid upon a supporting surface whereas if cylindrical it would be liable to roll.

I claim:—

A computing device comprising an exterior casing which is polygonal in cross section; an interior member mounted axially for rotation in such casing, and exterior means for rotating it, the interior member having upon its rotating surface characters arranged in circumferential columns and longitudinal lines of which a plurality of characters in the same longitudinal line are to be consulted simultaneously, the exterior casing having in each of its sides longitudinally aligned side apertures for disclosing said characters as said interior element is rotated.

In testimony whereof, I have hereunto set my hand at Chicago, Illinois, this 12th day of September, 1914.

BALTZAR E. BOLLING.
